UNITED STATES PATENT OFFICE.

EDWIN F. MAXWELL, OF WEST BRIDGEWATER, MASSACHUSETTS.

SOLE-EDGE TRIMMER.

SPECIFICATION forming part of Letters Patent No. 625,115, dated May 16, 1899.

Application filed March 12, 1898. Serial No. 673,564. (No model.)

To all whom it may concern:

Be it known that I, EDWIN F. MAXWELL, of West Bridgewater, in the county of Plymouth and State of Massachusetts, have invented certain new and useful Improvements in Sole-Edge Trimmers, of which the following is a specification.

This invention has relation to machines or tools for trimming the edges of the soles of boots and shoes; and it has for one of its objects to provide a device of the character specified which shall be so constructed as to discharge the cuttings more readily than heretofore, and consequently preserve the cutting edges.

Another object of the invention is to increase the adaptability and efficiency of the device by providing it with guards or means for limiting the depth of cut of the cutters; and a further object is to provide parts which may be readily removed for grinding and replaced when worn down.

The invention consists in the novel features of construction and arrangement, which I shall now proceed to describe and claim.

Of the accompanying drawings, forming a part of this specification, Figure 1 represents a side elevation of a sole-edge trimmer constructed in accordance with my invention. Fig. 2 represents a front or end elevation thereof. Fig. 3 represents a section on line 3 3 of Fig. 2. Fig. 4 represents a section on line 4 4 of Fig. 2. Fig. 5 represents a section on line 5 6 of Fig. 3 looking in the direction of the arrow x. Fig. 6 represents a section on the same line looking in the direction of the arrow y. Fig. 7 represents a front elevation of the trimmer with the shield and shield-support removed. Fig. 8 represents a perspective view of the shield and shield-support. Fig. 9 represents a front elevation of the same. Fig. 10 represents a side elevation of the same. Fig. 11 represents a front elevation of the cutter member. Fig. 12 represents a side elevation thereof. Fig. 13 represents a front elevation of the bottom-guard and its support. Fig. 14 represents a side elevation thereof. Fig. 15 represents a front elevation of the adjustable edge-guard. Fig. 16 represents a side elevation thereof.

The same reference characters indicate the same parts in all the figures.

Referring to the drawings, *a* is the shaft or spindle of the trimmer, and *b* is a sleeve adjustably secured on said spindle by means of a set-screw *b'* and formed at its outer end with a number of sections *b²* of the bottom-guard.

c is a shield-support secured to the end of the spindle *a* by means of a screw *c'* and formed with apertures *c²* for the escape of the cuttings.

c³ is a shield screwed to the shield-support *c* on the left-hand thread and provided with holes *c⁴*, with which a spanner may be engaged to secure or remove the shield.

d is the cutter member, formed as a spider, at the outer ends of whose arms are the cutters *d'*, having cutting edges at 2 2. As shown in the front views of this cutter member, its outer faces 3 3 are sloped toward the center to give cutting clearance. The cutters *d'* occupy the spaces between the sections *b²* of the bottom-guard and are set to leave spaces 4 4 between their forward faces and the rear faces of the sections *b²* for the purpose of allowing the cuttings to pass inwardly toward the center of the trimmer. The apertures *c²* in the shield-support are arranged to register with the spaces 4, as shown in Fig. 8, so that the cuttings may pass through said spaces and apertures and escape in the direction of the arrows *z*.

e is a ring which slips loosely over the screw-threaded outer surface of the sleeve *b*. This ring is formed with a number of radial apertures or recesses *e'*, in which are mounted horizontal forwardly-extending plates *e²*, which project through apertures *b³* in the bottom-guard and form an edge-guard for the cutters, as hereinafter explained. The forward ends of these plates occupy a shallow groove *c⁵* in the shield *c³*, said shield abutting closely against said plates when the trimmer is assembled, so as to hold them at their proper adjustment. The plates *e²* are arranged to be adjusted in and out in a radial direction by means of set-screws *e³* in their rear ends, and said rear ends are arranged to be clamped in place when adjusted by means of a retaining-ring *e⁴*, held to the ring *e* by means of screws *e⁵*, a nut *e⁶*, which screws on a threaded rear portion of the ring *e* and is provided with a milled periphery, enabling it to be screwed

on and off by hand, and a peripheral retaining ring or band e^7 . f is a second milled nut screwing on the threaded portion of the sleeve b and abutting against the nut e^6 . This nut 5 f operates to lock the nut e^6 , and also serves as a rear clamping member for the edge-guard. The front clamping member, as before stated, is the shield c^3 . The edge-guard may therefore be adjusted forward and backward and 10 secured in place by the two clamping members.

The cutter member d is formed with a sleeve which surrounds a reduced portion of the spindle a and is held between the shield-support 15 c and a shoulder 5 , formed by reducing the end of said spindle. The sections b^2 of the bottom-guard may, by moving the sleeve b longitudinally of the spindle toward or away 20 from the cutters d' , be adjusted to expose a greater or less portion of said cutters between the bottom-trimming edges 6 and the edges 25 7 of said sections b^2 . (See Fig. 4.) The depth of the cut made by the trimmer on the bottom of the sole is thereby regulated. This 30 method of adjustment also affords means for placing wide or narrow cutters for different thicknesses of soles in the same cutter-head and adjusting the bottom-guard to the bottom trimming edges of the cutters. It will be noted 35 that the cutters d' are recessed on their rear portions, as at 9 , to admit the portions of the bottom-guard between the sections b^2 . These recesses 9 differ in width for the different 40 widths of cutters.

35 The depth of cut of that portion 8 of each cutter which trims the vertical edge of the sole is regulated by adjusting the plates e^2 , forming the edge-guard before mentioned, in or out in a radial direction, and thereby exposing a greater or less portion of the cutters. 45 After continued use the cutters of an edge-trimmer become dull and it is necessary to grind them down. It will readily be seen that my improved construction enables the 50 various parts of the trimmer to be adjusted to take up this wear. As the cutter member becomes reduced in diameter by grinding, it is necessary also to reduce the diameter of the shield c^3 . The removability of said shield 55 from its support allows this to be easily effected and also permits the shield to be replaced without replacing the entire support.

Having thus explained the nature of my in-

vention and described a way of constructing and using the same, although without having attempted to set forth all the forms in which it may be embodied or all the modes of its use, I declare that what I claim is—

1. In a sole-edge trimmer, a rotary cutter member having edge-trimming portions 8 , 60 and a guard having portions adjustable radially toward and away from said edge-trimming portions to vary the depth of cut thereof.

2. In a sole-edge trimmer, a series of cutters, and bottom and edge guards occupying 65 the spaces between said cutters and arranged so that channels are left between the cutters and the members of the guards for the escape of cuttings inward toward the center of the trimmer.

3. In a sole-edge trimmer, a series of cutters, bottom and edge guards occupying the 70 spaces between the cutters and arranged so that channels are left between the cutters and the members of the guards, and a shield-support having a portion extending inside of the cutters, the said portion being formed with 75 apertures which register with the channels and constitute therewith passages for the escape of cuttings inward toward the center of 80 the trimmer.

4. In a sole-edge trimmer, a series of cutters, and an edge-guard consisting of a rear support or base, a series of plates secured thereto and extending horizontally between 85 the cutters, and means for adjusting said plates radially on their support.

5. In a trimmer, a cutter member comprising the spider d and the forwardly-projecting cutters d' thereon, and the cupped shield-holder c located inside of said cutters and formed with the peripheral apertures c^2 registering with the spaces between said cutters.

6. In a sole-edge trimmer, a spindle, a shield 95 removably secured to the end of said spindle, a series of cutters, a guard having portions which extend horizontally between said cutters and abut against the shield, and means for moving said guard horizontally of the spindle to clamp it against the shield.

In testimony whereof I have affixed my signature in presence of two witnesses.

EDWIN F. MAXWELL.
